PNEUMATIC TIRE TREAD AND BUTTRESS

James H. Bierbusse, Grosse Pointe Woods, Mich., assignor
to Uniroyal, Inc., New York, N.Y.

Filed Apr. 26, 1972, Ser. No. 247,931

Term of patent 14 years

Int. Cl. D12—15

U.S. Cl. D12—142

FIG. 1 is a perspective view, partly schematic, of a pneumatic tire tread and buttress embodying my new design, it being understood that the pattern is repeated throughout the circumference of the tread and buttress, as shown schematically by solid lines, and that the buttress pattern is repeated on the opposite side;

FIG. 2 is an enlarged fragmentary developmental plan view of the tread and buttress of FIG. 1; and

FIG. 3 is a sectional view of the tread and buttress, taken substantially as indicated by line 3-3 of FIG. 2.

I claim:

The ornamental design for a pneumatic tire tread and buttress, substantially as shown and described.
